(57) **CLAIM**

The ornamental design for an combination electric toothbrush and travel case, as shown and described.

DESCRIPTION

FIG. 1 is a front, top and right side perspective view of a combination electric toothbrush and travel case, showing my new design, with the travel case being shown separately for clarity of illustration; and

FIG. 2 is a rear, bottom and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front, top and right side perspective view of the electric toothbrush, shown separately for clarity of illustration;

FIG. 10 is a front elevational view thereof;

FIG. 11 is a rear elevational view thereof;

FIG. 12 is a left side elevational view thereof;

FIG. 13 is a right side elevational view thereof;

FIG. 14 is a top plan view thereof;

FIG. 15 is a bottom plan view thereof; and,

FIG. 16 is an exploded view of the combination electric toothbrush and travel case, thereof.

The broken lines in the drawings depict portions of the combination electric toothbrush and travel case that form no part of the claimed design.
